(74) *Attorney, Agent, or Firm*—Joseph B Bowman

(57) **CLAIM**

The ornamental design for a lacrosse head frame, as shown and described.

DESCRIPTION

FIG. 1 is a front elevational view of a lacrosse head frame showing a preferred embodiment of my new design;

FIG. 2 is a left side elevational view thereof and being a mirror image of the right side thereof;

FIG. 3 is a bottom plan view thereof;

FIG. 4 is a rear elevational view thereof;

FIG. 5 is a top plan view thereof; and,

FIG. 6 is a perspective view thereof.

1 Claim, 3 Drawing Sheets

FIG. 4

FIG. 5

FIG. 6
